UNITED STATES PATENT OFFICE.

ALBERT A. TINKER, OF MADISON, WISCONSIN.

FLOUR-CABINET.

SPECIFICATION forming part of Letters Patent No. 468,709, dated February 9, 1892.

Application filed September 26, 1891. Serial No. 406,961. (No model.)

To all whom it may concern:

Be it known that I, ALBERT A. TINKER, residing at Madison, Dane county, Wisconsin, have invented a new and Improved Flour-5 Cabinet, of which the following is a specification.

My invention is an improved flour or kitchen cabinet, and has for an object to provide a simple novel construction which will efficiently serve its purpose, be neat in appearance, and afford ample ventilation throughout.

The invention consists in certain novel constructions and combinations of parts, as will 15 be hereinafter described, and pointed out in the claims.

In the drawings, Figure 1 is a front view of the cabinet with the molding-board open. Fig. 2 is a vertical transverse section thereof, 20 the board being closed in full lines and open in dotted lines.

In its upper end the cabinet is divided into compartments A, the front walls of which incline rearward at *a* toward their lower ends, 25 and such compartments open into bins B, which extend forward in advance of the compartments A and are open at the top in front of such compartments, as shown, the inclined walls *a* of the compartments A serving to direct the contents of the compartments A to the rear of the bins B, and also affording better access to such bins.

In defining the parts A as "compartments" and the parts B as "bins," the compartments 35 may be said to end and the bins begin on a horizontal line drawn close to the lower edge of the front wall *a*.

To the outer side of the front wall *a* near its lower edge, I hinge one edge of the inside 40 lid or cover B², which may be turned down onto the forward extension of the bins B to form a cover therefor, and when so turned down the lid inclines downward toward its front end, so that any particles of flour or the like thrown 45 thereon in the operation of working upon the molding-board D, presently described, will readily pass or can be brushed down off the cover B² onto such board D. When desired, this inside lid B² may be turned up against the 50 front wall *a* of the compartments A, and the molding board or leaf, presently described,

can be opened or closed in either the open or closed position of the inside lid.

The cabinet is provided with a front plate or ledge C, arranged in a plane below the 55 plane of the bottom B' of the bins and with its rear edge in advance of the front edge of the said bottom B', as most clearly shown in Fig. 2.

The molding board or leaf D is made of a 60 thickness equal to the distance between the planes of the ledge C and bottom B', so that when such board or leaf is lowered it will bear at its under side upon the ledge C and at its upper side against the under side of the 65 bottom B'. This board or leaf D is pivotally jointed at E to the framing at a point in advance of its rear end and swings at such rear end in the space between the ledge C and bottom B', and is smooth and unobstructed 70 on its upper side at its rear edge, so that when such board or leaf is tilted flour and the like may be scraped off such rear edge into the drawer F, presently described. At the same time the pivotal axis E is so arranged that 75 when the leaf D is closed its rear extension abuts the rear edge of the ledge C, the axis E being preferably arranged above and slightly in rear of the said ledge, as shown.

The drawer F is arranged below the ledge 80 C, and stop devices are provided to limit the rearward movement of such drawer, so that when it is pushed to its innermost position an air passage or space G will be left behind it so that air can freely circulate behind such 85 drawer. Consequently the air is free to circulate from the lower compartment H up behind the drawer and then freely in front of the bins, thus affording ample ventilation to the flour or other materials in the bins when 90 the inside lid is opened and turned up against the wall *a*, as before described.

The door I of the lower compartment H is provided with wire-gauze or the like, so that air can freely circulate into and out of such 95 compartments.

Having thus described my invention, what I claim, and desire to secure by Letters Patent, is—

1. In a cabinet, substantially as described, 100 the combination of the bins, the ledge C, arranged below and in advance of said bins,

the drawer below the said ledge, and the board or leaf pivotally connected at a point in advance of its rear end and having its portion in rear of its axis arranged to swing in the space between the bins and ledge and having its upper side at its rear edge unobstructed, whereby when the board is tilted material may be scraped or freely discharged off its said rear edge into said drawer, all substantially as described, and for the purpose set forth.

2. The improved cabinet, substantially as herein described and shown, consisting of the compartments A, having inclined front sides ¹⁵ *a*, the bins B below such compartments A, the ledge C, arranged in front of and below the bins, the drawer arranged below the ledge and stopped at its rear end short of the back of the case, whereby air can circulate in rear ²⁰ of such drawer, the lower door having wire-netting or the like, and the molding board or leaf made of a thickness equal the distance between the planes of the ledge C and bottom of bins B, such leaf being pivotally con-

nected at E in advance of its rear end and arranged when opened to abut the under side of the bin-bottom in rear of its axis and the upper side of the ledge C in advance of such axis and when closed to leave a space or air-passage in front of the bins, all substantially ²⁵ ³⁰ as and for the purpose set forth.

3. In a cabinet, substantially as herein described, the combination of the compartments A, having front side or wall *a*, the bins B below and extended in front of the compartments A, the inside lid hinged at one edge to the wall *a* above such forward extensions of the bins and adapted to turn up against said wall in its open position or down to cover the bin B in its closed position, and the molding board or leaf arranged below said bins, all substantially as and for the purposes set forth.

ALBERT A. TINKER.
